W. P. CAPP'S

GAS PRESSURE REGULATOR

Filed Oct. 16, 1922

WITNESS:

J. S. L. Wright

Victor J. Evans

ATTORNEY

UNITED STATES PATENT OFFICE.

WILLIAM P. CAPPS, OF SHREVEPORT, LOUISIANA.

GAS-PRESSURE REGULATOR.

Application filed October 16, 1922. Serial No. 594,928.

To all whom it may concern:

Be it known that I, WILLIAM P. CAPPS, a citizen of the United States, residing at Shreveport, in the parish of Caddo and 5 State of Louisiana, have invented new and useful Improvements in Gas-Pressure Regulators, of which the following is a specification.

This invention relates to pressure regulating devices, particularly to dry gasometers, and has for its object the provision of a 10 novel pressure regulating device of the diaphragm type in which the automatic control valve and operating parts therefor are entirely enclosed within the device itself instead of being exteriorly arranged as is the 15 common practice.

An important object is the provision of a device of this character which will be simple and inexpensive in manufacture, highly 20 efficient in use, positive in action, durable in service and a general improvement in the art.

With the above and other objects and advantages in view the invention consists in the details of construction to be hereinafter more fully described and claimed and illustrated in the accompanying drawings, in which:

- 30 Figure 1 is an elevation of the device,
Figure 2 is a longitudinal section and
Figure 3 is a section at right angles to
Figure 2.

Referring more particularly to the drawings the numeral 10 designates the casing or shell which is preferably slightly conical though it may be purely cylindrical if preferred. The open side of this shell is formed with an outwardly extending flange 11

40 against which is disposed the sheet rubber diaphragm 12 held in place by a cap 13 provided with an outwardly extending flange 14 clamped against the flange 11 by suitable bolts 15 or the like. At one side the shell is

45 formed with a threaded nipple 16 for connection with an outlet pipe and at a preferably diametrically opposite point the shell is provided with a threaded nipple 17 for connection with an inlet pipe. The nipple 50 17 leads to a passage member 18 within the shell, this passage member being also formed with a threaded opening 19.

Extending centrally through the diaphragm 12 is a stem 20 which has its outer 55 end smooth and slidably through a boss 21

on the cover 13, and which has its intermediate portion threaded and carrying clamping nuts 22 which bear against clamping washers 23 disposed against opposite sides of the diaphragm so that the diaphragm will be firmly clamped with respect to the stem 20.

Located within the shell 10 is a valve including a casing 24 having one end screwed into the threaded hole 19 and having its other end open and communicating with the interior of the shell. Rotatable within this valve casing is a plug valve 25 having an operating stem 26 projecting beyond one side of the casing 24 and carrying an angle lever 27 which is pivotally connected at 28 with the inner end of the stem 20.

In the operation it will be seen that gas entering the nipple 17 will pass through the passage 18 and out through the valve casing 24 into the shell 10, and that the gas will pass from the shell through the outlet nipple 16. The parts must of course be initially adjusted to the pressure desired. In the event that the gas pressure increases beyond the certain desired predetermined point the diaphragm 12 will bulge outwardly and this will result in longitudinal outward movement of the stem 20, owing to the fact that this stem is secured to the diaphragm. When the stem thus moves, the angle lever 27 will be rocked and this will result in partly closing the valve 25 so that the flow of gas through the device will be destroyed. In case the pressure drops too greatly the tendency of the diaphragm to move to an absolutely flat state will result in swinging the angle lever 27 in the other direction so that the valve will be opened to permit additional gas to flow into the shell.

From the foregoing description and a study of the drawings it will be apparent that I have thus provided a simply constructed and consequently inexpensive dry gasometer which will effectually operate to maintain gas pressure at a certain predetermined point the action being entirely automatic and the control devices being enclosed within the device itself so that they will be protected from injury and also from being clogged by dust and dirt. Owing to the simplicity of the construction and the fewness of the parts it is apparent that there is nothing to get out of order so that the device should have a long life and satisfactorily perform all of its functions.

While I have shown and described the preferred embodiment of the invention it is of course to be understood that I reserve the right to make such changes in the form, construction and arrangement of parts as will not depart from the spirit of the invention or the scope of the subjoined claim.

Having thus described my invention I claim:

- 10 A device of the character described comprising a shell having a cover, a flexible diaphragm held taut between the shell and its cover, a stem slideable through the cover

and secured to the diaphragm and passing therethrough, said shell having an outlet nipple and formed with a passage member leading from an inlet nipple, a valve located within the shell and including a casing communicating with said passage member and with the interior of the shell, a plug rotatable within the valve casing, an angle lever secured to the projecting end of said plug and a pivotal connection between said stem and the angle lever.

In testimony whereof I affix my signature.
WILLIAM P. CAPPS.
